United States Patent

Des. 239,149
Patented Mar. 16, 1976

239,149

FLOWERPOT HOLDER

Marianne Hussey, 189 Arkansas,
San Francisco, Calif. 94107

Filed July 18, 1974, Ser. No. 489,776

Term of patent 7 years

Int. Cl. D11—02

U.S. Cl. D6—137

FIG. 1

FIG. 2

FIG. 3

FIG. 4

FIG. 5

FIG. 6

FIG. 7

FIG. 1 is a perspective view of a flowerpot holder showing my new design.

FIG. 2 is a front elevational view thereof.

FIG. 3 is a side elevational view thereof.

FIG. 4 is a back elevational view thereof.

FIG. 5 is a top plan view thereof.

FIG. 6 is a side elevational view thereof, showing the side opposite that shown in FIG. 3.

FIG. 7 is a bottom plan view thereof.

I claim:

The ornamental design for a flowerpot holder, as shown and described.
